WALTER VAN E. THOMPSON, OF LOS ANGELES, CALIFORNIA, ASSIGNOR TO THOMPSON MANUFACTURING COMPANY, OF LOS ANGELES, CALIFORNIA, A CORPORATION OF CALIFORNIA

INTERMITTENT MOTION SPRINKLER

Application filed May 28, 1927. Serial No. 194,923.

This invention relates to irrigation sprinklers and particularly to types having movable or revolving nozzle-units.

Sprinklers having revolving nozzle-units are superior to stationary ones due to their ability to irrigate much larger areas than the sprinklers having stationary nozzle-units. A common type of sprinkler comprises a body and a revolvable nozzle-unit. This nozzle-unit has radially extending arms, at the outer ends of which are secured non-radial nozzles. The water passes from the body through the nozzle-units, egressing from the non-radial nozzles. There is a 10 action of the water on the nozzle-unit which causes it to revolve. Streams of water flow from the nozzles and irrigate a circular area around the sprinkler. In the common type of sprinkler the nozzle-unit rotates comparatively fast, which rotation produces a whipping action, this whipping action reducing the throw of the water and consequently reducing the area which is irrigated thereby.

It is an object of this invention to provide a sprinkler of the character mentioned which will irrigate a comparatively large circular area.

It is another object of the invention to provide a sprinkler of this character in which the nozzle-unit moves slowly through small arcs, pausing for a short interval of time between each movement.

A further object of the invention is to provide a sprinkler of the character mentioned in which the nozzle-unit moves intermittently through a portion of its path and continuously through another portion of its path.

A still further object of the invention is to provide a sprinkler which is adapted for irrigating parts of a circular area. A sprinkler having this feature is adapted for placement near the boundary of an area to be irrigated.

Other objects and advantages will be made evident hereinafter.

Referring to the accompanying drawings in which the invention is illustrated:

Fig. 1 is a diagrammatic view illustrating its utility.

Fig. 2 is an elevational sectional view through the invention.

Fig. 3 is a section taken on the line 3—3 of Fig. 2.

Fig. 4 is a section taken on the line 4—4 55 of Fig. 2.

Fig. 5 is a perspective view of a portion of the operating-unit of the invention.

Fig. 6 is a plan view of Fig. 5 showing the mechanism in one position.

Fig. 7 is a view similar to Fig. 6, but showing the mechanism in another position.

Fig. 8 is a section taken on the line 8—8 of Fig. 2.

Fig. 9 is a section taken on the line 9—9 65 of Fig. 2.

The form of the invention shown in the drawings provides a shell 11 which includes a cylindrical member 12 having an upper head 13 and a lower head 14 which are 70 threadedly secured to the member 12, as shown. A casing 20 is extended around the shell 11 so that it encloses the shell and so that an annular shoulder 22 engages the upper head 13. A radial wall 23 is formed at 75 the upper end of the casing 20 which has a central opening 24.

Resting on an annular face 26 of the lower head 14 is a strainer 27 having a multiplicity of openings 28 formed therein. Water which is supplied to the shell 11 through a pipe 30 threaded to the head 14 at 31 is deprived of particles of foreign matter by the strainer 27. A sleeve 33 which fits snugly in the shell 11 is placed above the strainer 27, and an impeller-plate 34 is placed in the shell 11 so that it rests on an upper face of the sleeve 33. As shown best in Figs. 2, 8 and 9, the impeller-plate 34 has depressions 36 which provide water passages 37. The passages 37 are so constructed that water flowing therethrough is caused to flow in the direction indicated by the arrow 38 of Fig. 9. A cylindrical spacer 40 is inserted in the shell 11 above the impeller-plate 34.

Placed above the spacer 40 is an operating-unit 41 of the invention. A box which forms a part of the operating-unit 41 is composed of a cup-shaped member 42 and a cover 43. The cup-shaped member 42 has a radial wall 100

44 from which there projects an annular flange 45 which contacts the inner face of the cylindrical member 12 and which has openings 46 provided therein. Extending upward 5 from the peripheral part of the radial wall 44 is a cylindrical wall 48. As clearly shown in Fig. 2, the cylindrical wall 48 is substantially smaller in diameter than the inner face of the cylindrical member 12 of the shell 11, thus providing a substantially annular space 49. The cover 43 has a radial wall 51, the periphery of which engages the inner face of the member 12, and has openings 52 positioned in the outer annular area thereof which communicate with the space 49. The cup-shaped member 42 and the cover 43 are secured together by screws 56, as shown in Fig. 4, which project through the cover and through lugs 57 20 formed on the cup-shaped member 42.

In a rotor chamber 60 provided between the operating-unit 41 and the impeller-plate 34 is a rotor 61 which has a web 63. Extending from an outer annular radial portion of the web 63 are non-radial depending vanes 66. The rotor is secured to the lower end of a rotor-shaft 68, which rotor-shaft extends through a bearing 69 of the cup-shaped member 42. The upper end of the rotor-shaft 68 25 extends inside the box and has a small gear 70 secured thereto. The gear 70 meshes with a gear 71 which is rotatable on a shaft 72. As illustrated in Fig. 2 the lower end of the shaft 72 is supported by the radial wall 44 of the cup-shaped member 42 and the upper end thereof is supported by a cross-web 73. The gear 71 is formed integrally with or attached to a gear 74 which rotates therewith. The gear 74 which is a small gear meshes with 30 and drives a gear 75 which is rotatably supported on a shaft 76. The shaft 76 is supported at its lower end by the radial wall 44 and at its upper end by the web 73. The gear 75 is adapted to rotate a pinion-gear 77 which 35 is secured to a crank-shaft 78. The upper and lower ends of the crank-shafts are supported in sockets formed in the radial wall 44 and the radial wall 51 of the cup-member and cover.

50 The crank-shaft 78 has an upper or primary crank 79 and a lower or secondary crank 80. Pivoted on a shaft 82 which extends vertically in one side of the interior of the box is a primary pawl 83 and a secondary pawl 84. The end of the primary pawl 83 has a slot 85 in which the primary crank 79 operates, and the secondary pawl 84 has a slot 86 in which the secondary crank 80 operates. As the crank-shaft is rotated, the primary 55 and secondary pawls move from the positions illustrated in Fig. 6 into the positions illustrated in Fig. 7.

Extending through a bearing 89 of the cover 43, as shown in Fig. 2, is a drive-shaft 65 90. The lower end of the drive-shaft 90 ex-

tends into the interior of the box and has a primary ratchet-wheel 91 and a secondary ratchet-wheel 92 attached thereto. The ratchet-wheel 91 has teeth or projections 94 which are spaced a distance apart which is greater than their width, and the ratchet-wheel 92 has teeth or projections 95 which are spaced apart a distance equal to that of the teeth 94. The teeth 94 and the teeth 95, however, are offset in vertical planes as illustrated in Figs. 5, 6 and 7. The primary ratchet-wheel 91 is in the same horizontal plane as the primary pawl 83, and the secondary ratchet-wheel 92 is in the same horizontal plane as the secondary pawl 84. As 70 shown in Figs. 3 and 5, portions of the primary and secondary ratchet-wheels 91 and 92 are smooth, as indicated at 96. The mechanism described in this paragraph constitutes 75 the operating-unit of the invention. The operating-unit is divided into a controlled-means which includes the primary and secondary ratchet-wheels 91 and 92 and a controlling-means which includes the other mechanism of the operating-unit.

The parts of the invention located inside the shell 11 are clamped in place by clamp-pins 98 which thread through the upper head 13, the lower ends of the clamp-pins engaging the cover 43 of the box. For the purpose 80 of lubrication, I desire to fill the box with a soft grease.

The upper end of the drive-shaft 90 is provided with a drive-member 100 having a drive-tongue 101. The drive-tongue 101 extends into a slot 102 formed in a head 103 of a tube 104, this tube 104 forming a part of the nozzle-unit of the invention. The tube 104 extends through an opening 105 provided in the top of the shell 11. A shoulder of the head 103 prevents the tube 104 from being forced from the position shown in Fig. 2. The upper end of the tube has a radial arm 113 connected thereto. The outer end of the radial arm 113 is provided with a nozzle 115 which extends tangentially with a circle generated around the center of the tube 104. This construction just described comprises 95 the nozzle-unit of the invention.

Water supplied to the sprinkler flows into 100 the shell through the pipe 30, passing through the strainer 27. The water passes through the passages 37 and the impeller-plate 34, being caused to flow in the direction indicated by the arrow 38 of Fig. 9. The 105 water passes into the rotor chamber 60 and strikes the vane 66 of the rotor 61 and causes it to rotate. The water passes from the rotor chamber 60 through the openings 46 and through the annular space 49 into the chamber in the shell 11 above the operating-unit 41. The water passes from this chamber into the lower end of the tube 104 and is directed to a nozzle 115. In view of the fact that the nozzle 115 is non-radial, the stream of water 110

is directed so that a reaction is placed on the nozzle-unit which tends to rotate it.

The rotation of the rotor 61 operates the gears 70, 71, 74, 75 and 77 which operate the 5 crank 78. When the crank is rotated, the primary and secondary pawls 83 and 84 are alternately moved from the positions shown in Fig. 6 into the positions shown in Fig. 7. When the primary and secondary pawls are 10 in the position shown in Fig. 6, the primary pawl 83 is in position to be engaged by one of the teeth 94 of the primary ratchet-wheel 91. The secondary pawl 83 at this time is in a retracted position and is out of the path of 15 the teeth 95 of the secondary ratchet-wheel 92. At this time the primary pawl 83, due to its engagement with one of the teeth 94, prevents the nozzle-unit from being rotated by the reaction torque produced by the stream of 20 water issuing from the nozzle 115. As the rotor 61 is turned, the interconnecting chain of gears moves the crank 78 so that the primary and secondary pawls 83 and 84 move 25 into the positions shown in Fig. 7. The primary pawl 84 at this time moves into a retracted position out of the path of travel of the teeth 94, whereas the secondary pawl 83 moves into a position in the path of travel of the teeth 95 and is engaged by one of the teeth 30 95 as shown in Fig. 7. Referring particularly to Figs. 6 and 7, I will designate the tooth 94 engaged by the primary pawl 83 in Fig. 6 by the numeral 120, and I will designate the tooth 95 engaged by the secondary pawl 84 35 in Fig. 7 by the numeral 121. It will be readily seen from Figs. 6 and 7 that the secondary pawl 84 moves into the path of travel of the teeth 95 before the primary pawl 83 moves out of the path of travel of the teeth 94. The 40 instant that the tooth 120 is disengaged, the nozzle-unit is free to rotate and it will rotate in a direction indicated by the arrow 122 of Figs. 6 and 7 until the tooth 121 has moved into engagement with the secondary pawl 84. 45 It will be seen that the nozzle-unit and the ratchet-wheels 91 and 92 have moved through that fraction of a revolution represented by the ratio of one-half the circular pitch of the teeth 94 or 95 to the pitch circle of the ratchet-wheels 91 or 92. This action repeats itself 50 during the operation of the sprinkler so that the nozzle-unit is permitted to intermittently move through small arcs. The result of this is that the stream of water issuing from the nozzle 115 will spray on one place for a short time, preferably about a second, and then the nozzle-unit will move a small distance so that the stream will spray on an adjacent area. This is a desirable feature in view of the fact 55 that it permits the largest possible area to be irrigated. By utilizing small intermittent movements of the nozzle-unit, it is possible to eliminate all whipping of the streams of water and thus increase their throw.

60 As previously pointed out, the portions 96

of the primary and secondary ratchet-wheels 91 and 92 are left smooth. When these smooth portions 96 of the ratchet-wheels come into the positions adjacent to the pawls 83 and 84, the nozzle-unit will rotate until one of the teeth 94 or 95 is engaged. It will be obvious then that during a portion of the revolution of the nozzle-unit the movement of the nozzle-unit will be intermittent, and during another portion of the revolution the motion 70 will be continuous. This construction is adapted for use when it is desired to irrigate one portion of the area much more than another portion thereof, and is very valuable where a portion of a circle is to be irrigated 75 and another portion is not to be irrigated; for example, when large areas are to be irrigated, certain of the sprinklers are placed away from the boundary of the areas and may irrigate an entire circular area, and other 80 sprinklers are placed near the boundary so that they cannot irrigate an entire circular area but only a segment thereof.

Referring to Fig. 1, the numeral 130 represents a sprinkler of the invention which 85 may irrigate a circular area defined by the dotted line 131. In this figure the numeral 133 indicates a sprinkler of a slightly different type which is placed near the boundary 90 134 of the area to be irrigated and which can 95 irrigate only a portion of a circular area indicated by the dotted line 135. The sprinkler 133 includes the mechanism shown in the other figures of the drawings. The sprinkler shown at 130 is constructed slightly different 100 inasmuch as the primary and secondary ratchet-wheels 91 and 92 have teeth 94 and 95 entirely around its periphery, as indicated by dotted lines 137 in Fig. 3, and has no smooth portions 96. This construction provides a 105 sprinkler in which the nozzle-unit will revolve intermittently during the entire revolution.

The sprinkler-unit 133 is provided with a flow-arrester which is in the form of a screen 110 140, the screen 140 being supported by a suitable bracket 112. The screen 140 is preferably arcuated and is placed on the side of the sprinkler 133 adjacent to the boundary 134. The smooth parts 96 of the ratchet-wheels 91 115 and 92 are arranged on the same side of the tube 104 of the nozzle-unit as the arm 113. When the arm 113 reaches the position indicated by dotted lines 143, the smooth parts 96 come into adjacency with the primary 120 and secondary pawls 83 and 84, and the nozzle-unit will swing quickly and continuously until the arm reaches the position indicated by dotted lines 144 of Fig. 1, at which time the nozzle-unit will again move intermittently. It will be seen, therefore, that the arm 113, when it moves so that the stream issuing from the nozzle 115 will engage the screen, will move very quickly so that there 125 will not be an excess of water dropping from 130

the screen 140 at the boundary 134. When the arm 113 moves from the position indicated by dotted lines 144 into the position indicated by dotted lines 143 in Fig. 1, its movement 5 will be intermittent and the proper amount of water will be supplied to the portion of the circular area indicated by dotted lines 135.

I claim as my invention:

1. In a sprinkler, the combination of: a 10 reaction nozzle-unit adapted to move so as to supply water to an area to be irrigated; means for supplying water to said nozzle-unit; and an operating-unit actuated by the water supplied to said nozzle-unit adapted to stop the 15 rotation of said nozzle-unit for periods of time to render the motion of said nozzle-unit intermittent.

2. In a sprinkler, the combination of: a 20 nozzle-unit adapted to move so as to supply water to an area to be irrigated, said nozzle-unit being moved by the reaction of the water issuing therefrom; means for supplying water to said nozzle-unit; and geared operating-unit actuated by the water supplied to said 25 nozzle-unit adapted to stop the rotation of said nozzle-unit for periods of time to render the motion of said nozzle-unit intermittent.

3. In a sprinkler, the combination of: a 30 reaction nozzle-unit adapted to rotate so as to supply water to an area to be irrigated; means for supplying water to said nozzle-unit; and an operating unit adapted to stop the rotation of said nozzle-unit for short periods of time to make the motion of said nozzle-unit intermittent through very small arcs.

4. In a sprinkler, the combination of: a 40 nozzle-unit, said nozzle-unit being moved by the reaction of the water passing therethrough so as to supply water to an area to be irrigated; means for supplying water to said nozzle-unit; and an operating-unit adapted to stop the rotation of said nozzle-unit for periods of time to render the motion of said nozzle-unit intermittent, said operating-unit 45 including controlled-means connected to and adapted to move in synchronism with said nozzle-unit, and controlling-means for governing the movement of said controlled-means.

5. In a sprinkler, the combination of: a 50 rotatable sprinkler-unit, said sprinkler-unit being moved by the reaction of the water passing therethrough; means for supplying water to said sprinkler-unit; and an operating-unit adapted to stop the rotation of said nozzle-unit for short periods of time so that said nozzle-unit moves continuously during one part of its revolution and intermittently during another part of its revolution, said operating-unit including controlled-means connected to and adapted to move in synchronism with said nozzle-unit, and controlling-means for governing the movement of said controlled-means.

6. In a sprinkler, the combination of: a

nozzle-unit, said nozzle-unit being moved by the reaction of the water passing therethrough so as to supply water to an area to be irrigated; means for supplying water to said nozzle-unit; and an operating-unit adapted to stop the rotation of said nozzle-unit for periods of time to render the motion of said nozzle-unit intermittent, said operating-unit including controlled-means connected to and adapted to move in synchronism with said nozzle-unit, and controlling means operated by the water passing through said nozzle-unit for governing the movement of said controlled-means.

7. In a sprinkler, the combination of: a 80 rotatable sprinkler-unit, said sprinkler-unit being moved by the reaction of the water passing therethrough; means for supplying water to said sprinkler-unit; and an operating-unit adapted to stop the rotation of said nozzle-unit for short periods of time so that said nozzle-unit moves continuously during one part of its revolution and intermittently during another part of its revolution, said operating-unit including controlled-means connected to and adapted to move in synchronism with said nozzle-unit, and controlling-means operated by the water passing through said nozzle-unit for governing the movement of said controlled-means.

8. A combination as defined in claim 4 in which said controlled-means has projections, and in which said controlling-means has pawls adapted to engage said projections.

9. In a sprinkler, the combination of: a 100 rotatable sprinkler-unit, said sprinkler-unit being adapted to be rotated by the passage of water therethrough; means for supplying water to said sprinkler-unit; gears associated with said sprinkler-unit; a water-wheel; and 105 pawls associated with said water-wheel, said pawls being adapted to engage said gears to stop the rotation of said sprinkler-unit for short periods of time.

10. In a sprinkler, the combination of: a 110 rotatable sprinkler-unit, said sprinkler-unit being adapted to be rotated by the passage of water therethrough; means for supplying water to said sprinkler-unit; gears associated with said sprinkler-unit; a water-wheel; an 115 eccentric associated with said water-wheel; and pawls operably connected to said eccentric, said pawls being adapted to engage said gears to stop the rotation of said sprinkler-unit for short periods of time.

11. In a sprinkler, the combination of: a 120 shell; means for supplying water to said shell; a water-wheel rotatably mounted in said shell; an impeller-plate positioned in said shell, said impeller-plate being adapted to direct the water tangentially against said water-wheel; a shaft mounted in said water-wheel; an eccentric geared to said shaft; a nozzle-unit carried by said shell, said nozzle-unit being adapted to be rotated by the re- 125

- action of the water passing therethrough; a second shaft associated with said nozzle-unit; ratchets mounted on said second shaft; and pawls associated with said eccentric, said 5 pawls being adapted to alternate in engagement with their respective ratchets to stop the rotation of said nozzle-unit for short periods of time to make the motion of said nozzle-unit intermittent.
- 10 12. In a sprinkler, the combination of: a shell; means for supplying water to said shell; a water-wheel rotatably mounted in said shell; an impeller-plate positioned in said shell, said impeller-plate being adapted 15 to direct the water tangentially against said water-wheel; a shaft mounted in said water-wheel; an eccentric geared to said shaft; a nozzle-unit carried by said shell, said nozzle-unit being adapted to be rotated by the re- 20 action of the water passing therethrough; a second shaft associated with said nozzle-unit; ratchets mounted on said second shaft; pawls associated with said eccentric, said pawls being adapted to alternate in engagement 25 with their respective ratchets to stop the rotation of said nozzle-unit for short periods of time to make the motion of said nozzle-unit intermittent; a box in said shell surrounding said eccentric, ratchets and pawls, said box 30 journalling said shaft and said second shaft; and lubricant in said box.
13. In a sprinkler, the combination of: a nozzle-unit having means tending to rotate it continuously; means for supplying water to 35 said nozzle-unit; and means operated by the passage of water to said nozzle-unit for interrupting the rotation of said nozzle-unit to make its motion intermittent.
14. In a sprinkler, the combination of: a 40 rotatable sprinkler-unit, said sprinkler-unit being adapted to be rotated by the passage of water therethrough; means for supplying water to said sprinkler-unit; a gear associated with said sprinkler-unit; a water 45 wheel; and a pawl operatively connected with said water wheel, said pawl being adapted to engage and disengage said gear to intermittently interrupt the rotation of said sprinkler-unit.
- 50 15. In a sprinkler, the combination of: a rotatable sprinkler-unit, said sprinkler-unit being adapted to be rotated by the passage of water therethrough; means for supplying water to said sprinkler-unit; a gear associated with said sprinkler-unit; a water 55 wheel; an eccentric operatively connected with said water wheel; and a pawl operatively connected to said eccentric, said pawl being adapted to engage and disengage said gear to intermittently interrupt the rotation of said sprinkler-unit.
- 60 16. In a sprinkler, the combination of: a rotatable sprinkler-unit, said sprinkler-unit being adapted to be rotated by the passage of water therethrough; means for supplying 65 water to said nozzle-unit; and an operating-unit adapted to stop the rotation of said nozzle-unit for periods of time during a portion of its rotation to render the motion of said nozzle-unit intermittent during part
- water to said sprinkler-unit; gears associated with said sprinkler-unit, said gears having teeth formed only on one portion of the peripheries thereof; a water wheel; and pawls associated with said water wheel, said pawls being adapted to engage the teeth formed on said gears to stop the rotation of said sprinkler-unit for short periods of time during one portion of the rotation of the sprinkler-unit. 70
17. In a sprinkler, the combination of: a rotatable sprinkler-unit, said sprinkler-unit being adapted to be rotated by the passage of water therethrough; means for supplying water to said sprinkler-unit; gears associated with said sprinkler-unit, said gears having teeth formed only on a portion of the peripheries thereof; a water wheel; an eccentric associated with said water wheel; and pawls operatively connected to said eccentric, said pawls being adapted to engage teeth of said gears to stop the rotation of said sprinkler-unit for short periods of time during a portion of the revolution of said sprinkler-unit. 75
18. In a sprinkler, the combination of: a rotatable sprinkler-unit, said sprinkler-unit being adapted to be rotated by the passage of water therethrough; means for supplying water to said sprinkler-unit; a gear associated with said sprinkler-unit, said gear having teeth formed only on one portion of the periphery thereof; a water wheel; and a pawl associated with said water wheel, said pawl being adapted to engage the teeth formed on said gear to stop the rotation of said sprinkler-unit for short periods of time during one portion of the rotation of the sprinkler-unit. 80
19. In a sprinkler, the combination of: a rotatable sprinkler-unit, said sprinkler-unit being adapted to be rotated by the passage of water therethrough; means for supplying water to said sprinkler-unit; a gear associated with said sprinkler-unit, said gear having teeth formed only on a portion of the periphery thereof; a water wheel; an eccentric associated with said water wheel; and a pawl operatively connected to said eccentric, said pawl being adapted to engage teeth of said gear to stop the rotation of said sprinkler-unit for short periods of time during a portion of the revolution of said sprinkler-unit. 85
20. In a sprinkler, the combination of: a nozzle-unit designed so that the reaction of the water passing therethrough tends to continuously rotate same so as to supply water to an area to be irrigated; means for supplying water to said nozzle-unit; and an operating-unit adapted to stop the rotation of said nozzle-unit for periods of time during a portion of its rotation to render the motion of said nozzle-unit intermittent during part 90

of its travel and continuous during another part of its travel.

21. In a sprinkler, the combination of: a rotatable sprinkler-unit having means tending to cause its continuous rotation; means for supplying water to said sprinkler-unit; and an operating-unit adapted to stop the rotation of said nozzle-unit for short periods of time during a portion of the rotation of said nozzle-unit so that said nozzle-unit moves continuously during one part of its revolution and intermittently during another part of its revolution.

22. In a sprinkler, the combination of: a rotatable sprinkler-unit having means tending to cause its continuous rotation; means for supplying water to said sprinkler-unit; and an operating-unit adapted to stop the rotation of said nozzle-unit for short periods of time during a portion of the rotation of said nozzle-unit so that said nozzle-unit moves continuously during one part of its revolution and intermittently through small arcs during another part of its revolution.

23. In a sprinkler, the combination of: a rotatable sprinkler-unit having means tending to cause its continuous rotation; means for supplying water to said sprinkler-unit; an operating-unit adapted to stop the rotation of said nozzle-unit for short periods of time during a portion of the rotation of said nozzle-unit so that said nozzle-unit moves continuously during one part of its revolution and intermittently during another part of its revolution; and an arcuated flow-arrester against which said water issuing from said nozzle-unit strikes when said nozzle-unit is moving continuously.

24. In a sprinkler, the combination of: a rotatable sprinkler-unit having means tending to cause its continuous rotation; means for supplying water to said sprinkler-unit; an operating-unit adapted to stop the rotation of said nozzle-unit for short periods of time during a portion of the rotation of said nozzle-unit so that said nozzle-unit moves continuously during one part of its revolution and intermittently through small arcs during another part of its revolution; and an arcuated flow-arrester against which said water issuing from said nozzle-unit strikes when said nozzle-unit is moving continuously.

25. A combination as defined in claim 23 in which said flow-arrester is provided in the form of an arcuated screen.

In testimony whereof, I have hereunto set my hand at Los Angeles, California, this 21st day of May, 1927.

60 WALTER VAN E. THOMPSON.
